UNITED STATES PATENT OFFICE

JOHN L. SUTPHEN, OF PHILADELPHIA, PENNSYLVANIA, ASSIGNOR TO SCOTT & WILLIAMS, INC., OF NEW YORK, N. Y., A CORPORATION OF MASSACHUSETTS

AUTOMATIC SPLIT FOOT STOCKING KNITTING MACHINE

Application filed May 28, 1928. Serial No. 281,091.

This invention relates to making split tubular fabrics on automatic knitting machines of the kind having provision for beginning the knitting of each of a separate succession 5 of relatively complete stockings on the bare needles; for automatically knitting and fastening down a welt of the inturned kind; for knitting a stitch-length fashioned leg and ankle by single-course circular knitting; and 10 for completing the stocking by knitting an ankle, foot, heel and toe portions, provided if desired with sectional spliced reinforcements above the heel at the back of the ankle, at the heel, along the sole of the foot and 15 at the toe. An object of the invention is to provide new means in combination with the existing agencies of a machine of the kind mentioned so as to enable the machine automatically to knit the instep and the sole of 20 a stocking simultaneously by reversed partial courses interlocked at each side of the foot by a suture between selvages of respective 25 parts of the fabrics for the top of the foot and the sole; and, if desired, to knit the section at the back and above the heel of the stocking and the corresponding segment of the ankle of the stocking, by reversed partial courses interlocked at lateral sutures extending 30 in the direction of the wales of the knit fabric.

One object of this invention is to provide means for effecting split foot knitting in machines of the kind indicated which shall, so far as possible, utilize the existing agencies 35 of automatic machines for knitting stockings of a type not capable of knitting split and sutured structures. Another object of the invention is to provide operating means for existing devices for the purpose of knitting in the split tubular mode of knitting, the operating means being of a character adapted to be placed on machines already containing the complex devices necessary for the other uses 40 above mentioned, in such a way as to utilize the existing devices to make split tubular knitting and to avoid interfering with the function of the existing devices for starting on the bare needles, making welts, knitting heels and toes, and in general operating auto-

matically to produce relatively complete stockings in separate succession.

To the above ends, it will be observed that in machines of the kind having devices for making and fastening-off an inturned welt, 55 it is desirable to provide a series of instruments operating within and behind the needles adapted to receive and detain a course of the fabric, or bights in a course of the fabric in such a way as to allow the production of fabric for the welt; these devices must be such as to operate thereafter to transfer their withheld bights onto the needles for knitting the remainder of the stocking. It is therefore necessary to so provide the split-foot or split-leg knitting devices as not to 60 disturb the devices for taking and withholding the bights and not to disturb the devices cooperating with needles throughout the series of needles to cause them to receive the 65 bights from the bight-withholding devices. 70

In order to knit a split and sutured tubular structure by reversed part courses, devices for simultaneously forming and knitting at knitting waves respectively formed in 75 complementary series of a circle of needles are obviously necessary if the formation of both of the split portions of the tubular knit fabric is to proceed simultaneously, and as a corollary to this, it is desirable to equip a 80 knitting machine for knitting such tubular structures with devices for forming, feeding and holding down the web at an auxiliary knitting wave in one series of the needles only, and necessary to provide that these 85 auxiliary devices do not disturb the operations at the main or usual knitting wave.

In machines of the kind above mentioned devices are provided for knitting heels and toes by reciprocal motions through something 90 more than 180° of the needle circle of the main cams and yarn feed guide, and for the operation of narrowing and widening devices, so as to knit first a narrowed gore and then a widened gore on a segment of the 95 needles for a heel or toe pocket, during suspension of knitting on the needles of the remainder of the circle of needles. In order to provide for split-foot knitting, it is desirable that the devices for and the operation 100

of forming heels and toes in this familiar way shall not be disturbed, and one object of the present invention is to provide devices for the particular function of split tubular knitting which shall in part utilize the heel and toe knitting devices and which shall not disturb their operative function for their usual purposes.

In order to knit split tubular knitting by relative reciprocal motions between the needles and web-holder devices and their operating cams and yarn-feeding means, it is moreover desirable to utilize the existing devices for causing reciprocatory motion between the needles and their web-holders and the other operating parts. But for heel and toe knitting automatically, these reciprocatory motions are confined to a time and a duration corresponding only to the production of heel and toe fabric, whereas for the present purposes reciprocatory motion should begin in a predetermined relation to the point for heel or toe knitting, and precede or follow heel or toe knitting for the production of so much of the tubular fabric as is desired to be of split sutured formation; and therefore the machine should be provided with devices for change from rotation to reciprocation amenable to these uses; one object of this invention is to provide for so operating the existing reciprocating mechanical movement as to secure these results.

Since split-foot tubular knitting requires two knitting waves, provision is made according to this invention for feeding a knitting yarn for the second or auxiliary wave, and one of the objects of this invention is to provide devices consistent with the presence and operation of the welting and other stocking devices for automatically initiating the feed of a suitable yarn to the auxiliary wave, for withdrawing this yarn at the cessation of split tubular knitting, and for severing and holding it until it is again required to be fed.

The invention will now be explained in respect to a specific instance in which the automatic starting, welting, leg and heel and toe fashioning, driving and pattern mechanism and yarn feeding devices correspond to the well-known Scott & Williams machines, built, for example according to the Letters Patent of Robert W. Scott, No. 1,282,958, dated October 29, 1918 and No. 1,256,062, dated February 12, 1918. In the accompanying drawings,

Fig. 24 is an enlarged diagram elevation of the rear face of the fabric at any suture between the parts of the split tubular fabric; and

Fig. 25 is a diagram plan illustrating a typical arrangement of the series of needles.

Referring now to Fig. 1, the machine may comprise the usual frame 1 supporting the usual upper table or bed 2 for a knitting head comprising a needle cylinder 260 supported for rotation at the top of a hollow column 280, which may be utilized by lifting and lowering movements to lower or raise the needle cylinder for shorter or longer stitches. The machine comprises the usual drive shaft 32 adapted to be clutched to or disengaged from a driven gear, not shown, operated from the usual belt pulleys, or clutched to a gear 35 meshing with the rack sector 75 central on shaft 70 and adapted to be oscillated by a pitman and crank operated from the drive pulleys. The lateral position of

105

110

115

120

125

130

a clutch shifter element 92, Fig. 1, on the shaft 32, all as usual, thus determines whether or not a bevel gear 31 meshing with the bevel gear ring integral with or attached to the needle cylinder is driven to rotate, or to oscillate through an arc measured by the arc of oscillation of the sector 75. Also as usual in the art, the clutch shifter 92 on shaft 32 is automatically operated by coaction with a 10 cam track on a clutch drum 90 mounted fast on the shaft 80. Motions of the shaft 80 are the effect of advances through greater or lesser parts of the forward stroke of a pawl 82 on an eccentric stud 77 of and oscillating 15 with the sector 75, and having an effective stroke in contact with an irregularly toothed racking wheel 81 fast on the shaft 80, as determined by a controller for pawl 82, not shown, rocking on the shaft 93, and positioned by lugs of different heights on the 20 mutuable link pattern chain 85 carried by a sprocket 84 fast to a ratchet 86 having a bearing on shaft 80 and constantly moved forward during the operation of the machine by 25 the pawl 87, also mounted on an eccentric pin on the sector 75. The effect of these pattern devices is, as usual, to move the shaft 80 forward intermittently after a predetermined number of revolutions of the drive shaft 32, 30 as determined by the position of lugs on the chain 85.

The operative agencies of the machine are controlled by cams either on the shaft 80 or on rotary bodies geared to and moving in unison therewith, except as they may be otherwise moved. The shaft makes one revolution during the progress of each complete cycle of the machine to knit a stocking or other article, and it is desirable to parcel out 40 periods of angular advance of the shaft 80 with economy, in order to enable a sufficient motion of the pattern mechanism to accommodate all of the shifts and changes to be made.

45 According to the present invention, the usual or base machine is provided to be operated reciprocally by clutching the shaft 32 to the pinion 35 during the operation of the machine to knit split tubular portions of the fabric, as well as during operation of the machine to knit heels and toes. But because it is necessary to make different dispositions of parts of the machine for split tubular knitting and for heel and toe knitting, it is provided by this invention to move the clutch shifting drum 90 without shifting the clutch, for the purpose of initiating heel or toe knitting, ceasing heel or toe knitting, and resuming split tubular knitting. The changes for this purpose over the machine of the Scott Patent No. 1,282,958 may comprise no more than providing inclines of the cam track on the drum 90 at a sharper inclination than usual, and providing extra ratchet teeth 81a, 81b in the rack wheel 81 for the purpose of

permitting short motions of the rack wheel 81 and drum 90 between actuations of the drum 90 effective to shift the clutch. These extra teeth 81a, 81b, shown in Fig. 1, need not be provided at a position corresponding to the formation of the toe of the stocking, but a short effective motion only of the rack wheel 81 by the pawl 82 may instead be provided by causing pawl 82 to take a tooth of the wheel 81 only toward the end of its forward stroke to shift the machine agencies to single course reciprocal knitting for the narrowed and widened toe pocket; shifts the shaft 80 to change from narrowing to widening; and shifts the clutch on shaft 32 to resume rotary knitting after making the toe. The pawl 82 may be controlled for this purpose as usual by the controller rocking on shaft 93, worked by a lug on chain 85.

Referring now to Figs. 1, 2, 3 and 4, Fig. 5 and Figs. 15 to 17, and 25, the needle cylinder 260 may be provided with a usual series of needles *n* having shorter operating butts than the usual complementary series of long butt needles *N*. These needles may be distributed in segments of substantially equal numbers, the needles *n* being operated upon to make the heel, toe and sole of a stocking such as that shown at *S* in Fig. 23 and the needles *N* corresponding to the instep, front 95 of the leg and top of the foot. In order to provide for knitting sutured fabric for the split tubular sections *i*, *h* at the front of the ankle and back of the ankle, and *f*, *s* at the top of the foot and sole, the segment 100 of needles *n* may overlap the segment of needles *N* at each end, and vice versa, the suture needles *n'* and *n''* of the shorter butt set intervening between the suture needles *N'* and *N''* and the remainder of the longer butt set. 105

If now reciprocal knitting is conducted on the needles respectively of each of these two series, a wale from the needles *n'* and a wale from the needles *N'* will be related to the remainder of the fabric in a suture between 110 selvages as illustrated respectively in the wales *a* and *b* in Fig. 24. The devices described below are preferably employed with needles so arranged.

A typical product illustrated in Fig. 23 115 may be assumed to comprise a stocking beginning at a course-wise selvage *w*, having a course containing transferred bights *w'*; having the inturned welt *W*, a stitch-length fashioned plain fabric leg *L*, and an ankle 120 and foot portion conjoined by the suture *a*, *b*, illustrated in Fig. 24. The sections *h*, above the heel, and *s* at the sole of this stocking may be knit of the same yarn or a different yarn from leg *L*, or the same yarn reinforced 125 by an additional yarn, and the narrowed and widened heel *H* and toe *T* may be knit of the same yarn as or different yarn from the sections *h* and *s*.

Also as illustrated in Fig. 23 the heel or 130

toe pocket (as illustrated the toe pocket T only) may be separated from the reciprocally knit tubular section f, s by a plain circular knit fabric, as indicated at r, r'. In terms of operation of the machine, split tubular knitting ends at the line z, z, the machine resuming rotary motion to knit the sections r, r', and resuming reciprocal motion to knit the toe pocket T. The usual looper's rounds, not shown, may be knit following the toe pocket T.

To effect the several operations producing products typified by Fig. 23, the machine is provided, Figs. 2 and 15 to 17, with the usual cam cylinder 261 having the usual knitting cams 6 and 7, the usual top center cam 8 and a bottom center cam 9. During rotary knitting the stitch cam 7 may be the leading stitch cam and the cam 6 the following cam, all of the needles passing above the cam 7 and beneath the cam 8 to knit at the cam 6, whereupon they are returned by the cam slope 5 to the tuck position illustrated by the level line of needle butts in Fig. 15. The construction, adjustments, and mode of operation of the cams 6, 7, 8 and 9 may be as usual in the art. Associated with the cams 6 and 7 narrowing pickers 650, 650 may be constructed and adapted to operate as usual. The cam groups 6, 7, 8, 9 may, as usual, be positioned at the rear of the machine under a series of yarn changing yarn guides F¹ to F⁶ adapted when operative to deliver their yarns from a throat F in the latch ring 550, and adapted when inoperative to withdraw their yarns upwardly and within the space defined by the needles. Withdrawn yarns are received above a dial cap d', as presently referred to. The yarn guides F¹ to F⁶ comprise the main yarn feed, and the knitting cams 6, 7, 8 and 9 are concerned with the formation of the main knitting wave.

Referring to Figs. 2, 5, 16 and 17, in order to make the suture a, b of Fig. 24, it is desirable not to tuck at the leading short butt needle n' or n², which may result if the narrowing pickers 650, 650 are left in operation whenever there are reciprocal motions between the cam and needle cylinders. Provision is therefore made for lifting the pickers 650, 650 out of operative position, as shown in full lines in Figs. 16 and 17, except for knitting for heel and toe, by a pattern operated connection. Arcuate horizontal levers 652, 652 pivoted between their ends on the main knitting cam support are provided to take under the pickers 650, 650, respectively at one end of each lever, the other ends overlapping behind the center cams, and, see Fig. 5, under the inner end of a lever 654 pivoted between its ends on bedplate 2, the outer end of lever 654 taking over a block 655 on the lateral face of one of the thrust-bars 460⁰, worked by cams on pattern drum 120. This thrust-bar may be that adapted to lift the yarn finger F¹

carrying the leg yarn, which is usually exchanged for another yarn appropriate for the section h upon beginning to make split tubular fabric. The block 655 may be so placed as to require an extra high lift of its thrust-bar to work the lever 654, and in that case, the pickers can be released to usual position without moving finger F¹ to feeding position.

For the purposes of the machine of the said Scott Patent No. 1,282,958, the machine also comprises devices for knitting a starting selvage, devices for taking and detaining bights, and devices for operating the needles and the devices for taking the bights to transfer the taken bights to the needles.

Referring to Figs. 1, 3, 4, 5, 7, 8 and 9, a dial bed d for the bight or loop taking and transfer implements is fast on the lower end of and driven by a dial shaft 3 concentric with cylinder 260 and held in a vertical bearing hub 14^a of a bracket 14 mounted on the latch ring 550 by a bevel gear 15 meshing with a pinion 16 on a horizontal shaft 17 also in bearings of bracket 14. Shaft 17 is driven by a bevel gear 18 meshing, when the latch ring 19 is operatively positioned, with a pinion 19 at the top of a vertical shaft 10 in an upright bearing bracket 11 mounted on bed plate 2, which is bored for shaft 10. At the lower end of shaft 10 a pinion 10^a meshes, Fig. 3, with a bevel gear 31^a formed on the needle cylinder driving bevel gear 31 fast on drive shaft 32. The dial d is thus driven in unison with the cylinder 260 whether the motion is rotary or reciprocating.

The dial cam cap d' has, see Fig. 8, a bearing hole d² in a central bore taking over the hub 14^a and is held against rotation by a steady pin d^a, Figs. 8 and 9, entering a hole in bracket 14. The dial cap receives withdrawn yarns on its upper surface.

Referring to Fig. 15, the needle cylinder 260 is provided with jacks 381 under alternate cylinder needles, and the cam cylinder 261 is provided with a groove 365 for the jack butts, which are advanced at a cam 366 to move alternate needles upwardly to pass above the leading stitch cam 7 and a radially movable dividing cam 382. When the cam 382 is operatively positioned, the needles not advanced by the jacks 381 are retracted beneath the stitch cams and at the slope 5 pass upwardly in front of the yarn, these being characteristic operations leading to the formation of a starting selvage on bare needles by the operation of the cam 382 and the jacks 381, as fully described in said Scott Patent No. 1,282,958.

Operating between the jack cam 366 and the cam 382, a movable depressing cam 12 is made use of to manipulate the needles for receiving bights of a transfer course, and with this may be associated an advancing cam 13 for delimiting the taking or transferring of bights to a single course. The cams 12

and 13 cooperate with transfer bits operating in radial grooves d^2 , Fig. 9, of dial d under the influence of cams carried by a cam block m movable on the dial cam cap d' to effect receipt of and transfer of detained bights, all according to said Patent 1,282,958. These devices being desirably employed in the making of stockings according to this invention, the remaining devices are required to cooperate with them. The construction and mode of operation of the said devices is arranged to remain substantially as described in the said patent.

According to the said Scott patents, the operation of the cams 382, 12 and 13, the operation of the yarn feed guides F^1 to F^5 , and the operation of the devices requiring to be moved for the purposes of making the product in relation to the dial cap d' are all controlled by thrust bars 460 supported in inclined positions at the rear of the machine and resting upon the periphery of a cam drum 120 on the shaft 70 driven by gearing 121 from a gear 122 fast on the shaft 80. At times the drum 120, shaft 80 and its attachments may be driven forward during a particular segment of angular motion of the needle cylinder, through short angular distances, by the pawl lever 431 reacting with cam 430 on shaft 32 and engaging occasional ratchet teeth on drum 120 to operate at exact times special needle cams. This mechanism is retained substantially unchanged, as appears at 12, 20, 382, 487 in Figs. 2 and 3.

The cam cylinder 260 is provided with the usual web-holder bed 295 for the usual web-holders 292 having butts adapted to be operated by a web-holder cam cap 300. So far as the coaction of the web-holders with the needles operating the main cams 6 and 7 is concerned, the devices may be the same as those in said Scott patents.

For the purposes of this invention the machine is equipped with auxiliary knitting cams, preferably operating at a point 180° displaced from the knitting cams cooperating with the main knitting wave. Referring now to Figs. 2 and 4 particularly, there may be provided for the auxiliary cams, above the bed plate 2, a slide 100 radial in respect to the needle cylinder and cam cylinder and adapted to move toward and away from the center of rotation of the needle cylinder in a way provided by hold-down plates 101, 101 screwed to the bed plate 2 and occupying the space between symmetrically arranged brackets 102 and 103 providing a bearing respectively for widening pickers 680, 681, their directing cams 682, 682, and their guard cams 683, 683. The standard 103 also carries above the space occupied by the slide 100 a vertical support 400 for the latch ring 550 and latch 558 (Fig. 4).

The slide 100 is provided with a vertical stud 105 which takes into a hole in a lever

106 pivoted at 107 on the bracket 102 and which is pivoted to a link 108 pivoted to a bell crank lever 109, Fig. 1, pivoted on an auxiliary frame 110, Figs. 1 and 2, secured to the bed plate 2 at the rear of the machine and over the pattern drum 120.

The frame 110 provides a bearing housing for the transmission of the indications of a series of thrust bars 465* operated by appropriate cams on the drum 120, and serving to adjust agencies of the machine concerned with the operation of the needles, feeding the yarn, and determining web-holder function at the auxiliary wave. For example, the thrust bar 466 guided in a comb 467 on stud 450 in a perforated plate 468 on the frame 110 reacts against the elbow of the pivoted bell crank 109 to move and hold, through link 108, the lever 106 and slide 100 against the stress of a spring 111 in its inward operative position.

Referring to Figs. 15 to 17, the slide 100 may comprise an arc-shaped plate 112 adjustably carrying the reciprocal stitch cams 113 and 114 and a top center cam 115. When the slide 100 is inwardly positioned these cams are radially positioned to engage and act upon the long butt needles N only. Preferably the arc-shaped carrier 112 is also provided with guard and advancing cams 116 and 117. The usual cam ledge of the cam cylinder 261 is cut away at 262 Figs. 2 and 15 to provide a free space for the motion of the cams carried by the slide 100 and the needles moved by them.

While the cams on the slide 100 and 112 may be relied upon to operate the long butt needles for reciprocal knitting upon them from a yarn fed in proper relation to the knitting wave in the long butt needles, it is necessary to provide that the long butt needles shall not knit at the cams 6, 7, and 8, with which they normally cooperate for rotary knitting, for example when making the leg or welt of the illustrative stocking. When it is desired to knit a heel or toe, it is provided that the long butt needles shall travel in their usual elevated position in relation to the main cams 6 and 7, and for heel and toe knitting the short butt needles should cooperate with a widening picker or pickers. The usual place for the operation of a widening picker is occupied by the auxiliary cams 114, 113, but right and left widening pickers 680, 681 may be positioned to take down the leading member of any series of needles reaching them on the far side, in the direction of travel, of the cams 113, 114, which are withdrawn out of reach of needles during heel and toe knitting. It is therefore desirable to provide for the elevation of the long butt needles not only for heel and toe knitting for the usual idling of an instep segment of the needles but, in a different sense, during their normal knitting activity

125 130

when knitting split tubular fabrics, in order to enable these needles to pass the main cams without there knitting, and without disturbing the performance of the short butt needles to knit at the main cam.

This invention provides for these purposes deflecting cams A and B, Figs. 2, 15, 16, 17 and 18, adapted to cooperate with the long butt needles only and means for automatically adjusting these deflecting cams to provide for switching the long butt needles above the main stitch cam and into the auxiliary stitch cam during split tubular knitting; to position the long butt needles at their upper idle level for heel and toe knitting; and to reposition the long butt needles for split tubular knitting after making a heel or toe.

Referring to Figs. 15, 16 and 17, it is preferred to place the deflecting cams A and B 20 asymmetrically in respect to the main stitch cams, so that the leading and following cams A and B respectively in the direction for rotary knitting may respectively follow the auxiliary cam group and the main cam group 25 at about the same distance. Preferably the deflecting cams A and B respectively are so constructed as to provide an inclined throat or passage for the long butt needles; for example as best shown in Fig. 18 each of these 30 cams may comprise a channel b' having one side b^2 long enough to react on any short butt needle n which may encounter it, and the other side b^3 too short to encounter short butts.

Referring to Figs. 2 and 3, the cam A 35 may be integral with or attached to the inner end of a slide 113^a held in a slide bracket 112^a mounted on the bed plate 2. Slide 113^a is provided with an enlarged head 114^a taking against a compression spring 115^a between it and face of the bracket 112^a, acting to withdraw the cam A from operative position. Pivoted at 116^a on a lug of the slide-way 112^a a lever 116^b is connected by a link 40 117^a to an arm 118 on a rock shaft 119 having a bearing in the frame 110. Shaft 119 is provided with an arm 130 overlying a thrust bar 468 of the series 465^a, and is therefore adapted to be operated at times determined 45 by an appropriate cam on drum 120.

Cam B is mounted on a slide 131 in a slide-way bracket 132 mounted on the bed plate 2, and provided with a compression spring 133 taking against its enlarged head 134, against 50 which a lever 135 pivoted at 135^a on a lug of slide-way 133 may be thrust by a link 136 connected to an arm 137 fast on a rock shaft 138 having bearings in frame 110. An arm 139 on shaft 138 overlies a thrust bar 469 of 55 the series 465^a. This thrust bar is also operated by an appropriate cam on drum 120.

When cams A and B are moved into operative position, see Fig. 16, during rotation of the needle cylinder in the direction of the 60 row x , Fig. 15, the cam A operates as a switch

or deflector cam to deliver the long butt needles N above the top center cam 8 of the main cam. Any needles N which may reach the cam B after passing the main cam are deflected back to their normal tuck position. 70

Any needles n which pass the cam B are not affected. The needles n pass across the face of the auxiliary cams 113, 114 whatever the relative direction of their motion and whatever the position of the slide 100 and sector 75 112.

It is desirable to make no changes of degree in the extent of the oscillatory arc swept by the needle cylinder when the pinion 35 is clutched to the shaft 32. In the machine 80 selected for illustration, the contact points between the ends of the segment of needle n and the segment of needles N, at which points the suture needles n' , N' , n^2 , N^2 are placed, oscillate through an arc somewhat less than 85 a whole revolution and having its end point for the leading short butt needle n' moving in the direction of the arrow y , Fig. 16, at the cam B, the leading needle N^2 then having reached the position of the cam A. In the 90 opposite direction (motion in the direction of the arrow x , Fig. 15) the leading short butts at the end of a stroke may reach the cam B, or stop in the relation shown in Fig. 17 to the cam A. In either case, it will be observed 95 that in respect to either of the set of needles n or the set of needles N, there has been a complete passage through the cams of the segment of needles intended to be operated by these cams. For example the short butt 100 needles n enter and pass completely through the cams 5, 6, 7, 8, 9, the last needles of this series resuming the normal tuck position after passage by the cams in each direction; and similarly the long butt needles N enter and 105 pass completely through the auxiliary cam group 113, 114, 115, the last needle of this series, moving in whichever direction, entering the cam A or the cam B at the end of the stroke. It will therefore be plain that before entry into operative position of the auxiliary cam, which entry occurs during passage of the short butts n , the leading needle on the next stroke of the long butt series is 110 properly positioned at the tuck position to enter the auxiliary cam.

This condition of position of the long butts is not however true whenever the machine, having been knitting split tubular fabric, resumes motion in the direction x for rotary 115 knitting, the cam A being withdrawn outwardly. In that case some of the long butt needles may be left in the position shown at the cam A in Fig. 17 on the retirement of that cam, and these needles would not then 120 certainly enter the main cams to knit.

This invention therefore provides a cam C adapted to be entered whenever rotary plain knitting is to follow split tubular knitting or split tubular knitting is to follow heel or toe 125 130

knitting. The cam C is a depressing cam, and as best shown in Figs. 2 and 3 may conveniently be mounted on slide 21^a superposed on the slide bracket 21 carrying the actuating slide 12^a for the cams 12 and 13, Figs. 15 to 17, which in the machine illustrated is operated by a horizontal lever 20 worked by a cam 462^a on a thrust bar 462. To enable the slide 21^a and cam C to be operated by this same connection, slide 21^a is provided with a headed stud 21^b and compression spring 21^c, the stud taking through a hole in a lug 21^d on the lever 20. These arrangements are such that the cam C is thrust in whenever the lever 20 is moved; but the cams 12 and 13 are moved only when the amplitude of motion of the lever 20 is sufficiently great to bring its end in contact with the slide 12^a. The thrust bar 462 may therefore be lifted by an appropriate cam on drum 120 to a lesser extent to move the cam C into operation than to move the cams 12 and 13. As mentioned above the cams 12 and 13 are used during transfer of the uniting course for the welt 25 W, and are not used during split tubular or heel or toe knitting.

In the machine of the said Scott Patent No. 1,282,958 alternate needles of both series provided with jacks 381 are raised to position to clear the cam 382 at each revolution of the machine by the operation of the cam 366. In the present machine, if this were permitted to take place throughout the operation, the short butt needles with jacks, which desirably should be left at the tuck position, would be left too high. It is therefore provided to move the jacks 381 to their full height only at times when the machine is not operating to make split tubular fabric. To this end the jack cam 366 may be cut away at its apex at 367 and provided with an auxiliary movable apex part 368 adapted to be moved to the full line position, Fig. 15, prior to beginning a new stocking. Preferably cam 368 is carried on a slide 369 in a vertical slideway cut in the outer thickness of the cam 366. Slide 369 may be lifted by a link 370 pivoted to it at 371, and in turn pivoted to a crank arm 372 on the inner end of a rock shaft 373, Figs. 2 and 3, in bearings on one side of the bracket 112^a, and provided with a crank head 374, normally rocked by a spring 374^a to hold the auxiliary jack cam 368 in the position of Figs. 16 and 17. When the auxiliary jack cam 368 is to be normally positioned as shown in Fig. 15, shaft 373 is rocked by a lifting movement of the thrust rod 375 extending through bores in the bed plate of the machine to contact with a cam 82^a fast on the gear 122 fast on the left end of shaft 80, see Figs. 1 and 19. The contact end of rod 375, Fig. 3, may carry a compression spring 375^a to insure lifting part 368 to its full height.

Whenever an auxiliary wave is formed in

the needles, it is desirable to provide for actuation of the web-holders 292 bearing the same relation to that knitting wave as the normal web-holder actuation wave bears to the main wave at cams 6 and 7.

70

Referring now to Figs. 11 to 14, the web-holder cam cap 300 is provided with the usual depending flange 302 having a running fit on a shoulder of the web holder bed 295, and restrained from rotation with the web holder bed by the adjustment screws 303 in lugs 304 except for an angular fall back motion in consequence of these provisions through the gaps between the ends of screws 303 and the faces of the standard 400.

75

The underface, Fig. 12, of the cam cap is provided with the usual groove 305 concentric throughout the greater part of its periphery but interrupted by a recess at the back of the machine for a fixed web-holder withdrawing cam 308, the groove 305 being provided with advancing shoulders 309. In order to provide for web-holder function at the auxiliary wave, the interior flange defining groove 305 of the cam cap is cut away at 310 to provide a space to receive a vertically movable web-holder withdrawing cam 312 adapted to operate through an arcuate slot 313 formed in the cam cap 300. The groove 305 is carried outwardly at 314 to provide an advancing cam surface for the web-holder butts. A few of the web-holders 292 corresponding to the end of the short butt series of needles n may have shorter butts than others to permit cam 312 to enter upon them from above.

80

Cam 312 is mounted on depending headed pins 315 extending through bores in a guide plate 316. The central pin 315 may have a projection 317 adapted to take over a lever 318 pivoted at 319 on a lug 320 of plate 316. The cam 312 is urged downwardly by compression springs 321, Fig. 14, surrounding one or more of the pins 315. One end of lever 318 extends through a slot in an angle plate 322 erected on the upper surface of the cap 300 and having pivoted thereto a spring latch 323 engaging lever 318 and having an outwardly projecting tail 324. The end of the lever 318 projects tangentially, Fig. 11, beyond the right-hand lug 304. When the lever 318 has been lifted against the stress of springs 321 the cam 312 is upwardly out of reach of the butts of web-holders 292 and is latched in this position by the latch 323. The cam 312 is put into action by depressing the tail 324 of the latch 323, and is taken out of action by lifting the lever 318 by its projecting end.

90

The cam 312 is moved into and out of operation by a vertically movable slide rod 326, Fig. 4, having a head 327 from which projects a pin 328 taking under the lever 318 and adapted to lift said lever on an upstroke of the rod 326. The head 327 also carries a cam latch 329 adapted to pass the tail 324 of the

100

105

110

115

120

125

130

latch 323 without unlatching the lever 318 but, when the slide 326 is depressed, serving to unlock the lever 318 and release the cam 312 to go into operation.

5 Slide rod 326 is suitably moved by any suitable connection to the pattern mechanism. As shown, Fig. 4, the lever 330 pivoted to rod 326 and at 331 on the underside of the bed plate 2 normally depresses the slide rod 326 by the stress of a spring 332. A lever 333, Fig. 1, pivoted on a depending lug 334 under the bed plate 2, at one end takes over a block 335 attached to the face of one of the thrust bars of series 465^a. A suitable cam on drum 120 therefore controls the vertical slide 326 to enter and withdraw the web-holder cam 312. Whenever the auxiliary cam wave is established in the long butt needles N the cam 312 is previously entered to withdraw the web-holders at the downgoing phase of this wave. It will be observed that the connections 318 to pin 328 and 324 to latch 329 are such as to enable the lost motion oscillation of the web-holder cam cap 300 to take place without breaking the operating connection.

Whenever the auxiliary wave is established in the long butt needles it is important that the leading needle shall be fed with a 30 yarn appropriate to the front part of the fabric being knit; for example, in the illustrative stocking, a yarn similar to the leg yarn and suitable for the sections *i* and *f*. The devices relied upon for this purpose are 35 of a kind desirably conforming to occupation of space by the dial bracket 14, the dial cap *d'*, the appurtenances carried by the dial cap, and the devices for operating these appurtenances.

40 Referring now to Figs. 1, 2, 3, 4, 5 and 7, as best illustrated in Figs. 1, 5 and 7 the latch ring 550 is provided with a gap closing annulus 565 adapted in one position to open the throat F through which the main yarn guides F¹ to F⁵ move when put into or withdrawn from operative position. In another portion of the device 565 there may be provided another gap, at the opposite side from the main yarn feed, as shown at 566, Fig. 6, 45 and, the latch ring 550 being appropriately recessed at 567, a yarn guide 570 for the auxiliary yarn may be entered into and withdrawn from the recess 567 to feed or cease feeding the auxiliary wave in needles N. 50 Preferably as shown in Figs. 5 and 6 the yarn guide 570 is pivoted well above and substantially in line with the cylindrical surface defined by the needles at 571, and the motions of its yarn feeding end are revolutions of 55 proper vertical motions of the pivot 571 and vibratory motions about the center 571. The guide 570 is adapted and arranged when in position in the recess 567 to provide by its interior face a continuation of the latch guard 60 surface of the ring 550. At other times, the

gap closer ring 565 is relied upon to bridge this recess. For this purpose the gap 566 in ring 565 for the auxiliary wave may in its position of rest be further displaced from the recess 567 than is the gap at throat F, so that a longer angular motion of gap closer ring 565 is required to open the auxiliary gap. 70

It is therefore provided to move the actuator ring 565 whenever the yarn is to be entered or withdrawn at F, and to move it further whenever the auxiliary yarn is to be fed or withdrawn from the auxiliary needle wave. For this purpose, see Fig. 1, there may be pivoted on the latch ring pivot standard 401 a lever arm 575 connected by a link 576 to the gap closer ring. A spring 566 tends to maintain the gap closer in its closed position. Lever 575 may be actuated through link 577 and two-armed lever 578 loose on the rock shaft 119 in frame 110. 80 The lever 578 takes over and is actuated by one of the thrust bars of the series 465^a as shown at 469. Appropriate cams of different heights (not shown) on drum 120 shift the latch ring further whenever the yarn 85 guide 570 is to be entered or withdrawn, and through a lesser angle whenever one of the main yarn guides feeding to the yarn throat F is to be shifted.

Assuming that the yarn guide 570 for the auxiliary wave is in the position shown in Fig. 5 and that the severed end of its yarn is held on the upper surface of the dial cap *d'*, devices are provided for placing the yarn guide 570 in position to be made operative 90 to feed the needle wave on the next reverse stroke (in direction *y*, Fig. 16) of needle cylinder 260. The yarn guide 570 depends from its pivot 571 through a slot in the forward arm of the bracket 14. The pivot 571 is 100 mounted in one end of a radius arm 573 pivoted at 574 to a bracket 575 erected on the latch ring. The radius arm 573 is pivoted at 576 to a trip 577 having a spur 579 normally in position to engage the upper surface of a stop 578. The upper end of the 105 yarn guide 570 is provided with a cam surface 579^a reacting with a fixed stud 580 on an extension of the bracket 575. The yarn guide 570 is also provided with a pin 581 110 adapted to rest on the upper side of a radius link 582 pivoted to bracket 575 and linked to a lever arm 583. 115

The auxiliary yarn guide passes to a preliminary operating position above and in line with the needles and is there stopped by the spur 579, whenever the arm 583 is dropped. Arm 583 is controlled to drop by attachment to a rock shaft 584, Figs. 3 and 7, at the back of the machine, which rock shaft is provided with an arm 585 having a stop 586 resting on a link 587 pivoted at 588, Fig. 3, to a lug on the standard 11, and connected at its other end to a vertical thrust rod 590, attached to a thrust bar and guided 120

by the front face resting against the stud 450, Fig. 3, and actuated by cams on drum 120.

5 The yarn guide 570 is to be dropped into operative position on the reverse stroke of the needle cylinder. Whenever the trip 577 is moved radially outwardly, the pin 580 determines an outward motion of the end of the yarn guide into the recess 567. When 10 the arm 583 is operated upwardly the yarn guide 570 is moved upwardly and inwardly in respect to the needles and the center of the machine; the pin 581 may be stressed downwardly by a light spring 595.

15 To move the trip 577 there is pivoted on the bed plate 2 of the machine a vertical lever 591 having a hook 592 adapted to be moved outwardly by contact of the upper end of a lever 593 pivoted at 595 on bracket 103, having 20 its lower end in contact with and to be moved by a part moving with slide 100, and adapted at its upper end to move outwardly against a pin 594 on lever 591, to move the lever 591 to release the trip 577 whenever 25 slide 100 is moved inwardly. This motion occurs prior to the first reverse stroke of reciprocation and after all of the needles N have passed the auxiliary cams.

Whenever the yarn for the auxiliary wave 30 is moved upwardly and inwardly, it is arranged to be received, clamped and severed on the upper surface of the dial cap d'. This will occur when the machine is about to resume rotary motion, as determined by actuation of the rod 590. One way of severing and clamping the withdrawn yarn is shown in Figs. 7, 8 and 9. In addition to the usual 35 yarn clamp f², Fig. 8, and the actuated yarn clamp f³ and actuated shears f⁴, a clamp f⁵ carrying a leather block f⁶ may be pivoted at f⁷ on the lug f⁸, and be held so that the block f⁶ bears against a surface of the dial cap by a spring f⁹, and be lifted to open the clamp 40 to receive the withdrawn yarn by a link f¹⁰ and lever f¹¹ pivoted on an existing stud f¹², Fig. 7, and actuated by a link f¹³, two-armed lever f¹⁴, Fig. 1, and one of the thrust bars of the series 465^a and cams on drum 120. There 45 may also be erected upon the upper surface of the dial cap a ledger blade f¹², against one upwardly extending diagonal edge of which a shear blade f¹³ pivoted at f¹⁴ is actuated by a link f¹⁵, also connected to lever f¹⁰. As shown in Fig. 10 the link f¹⁵ 50 may be attached to the lever f¹⁰ for lost motion in the slotted hole f¹⁷.

In order to avoid the construction just described for coordinating the motions of a mechanically actuated clamp and cutter with the operations of the auxiliary yarn guide 570, resort may be had to a spring clamp q, Fig. 21, like the clamp f² of Fig. 8, and to a fixed cutter q', which may comprise a triangular fixed knife blade held in a slot in 55 the upper surface of the dial cap d¹, and

preferably protected by a U-shaped guard q² having a sloped under edge q³. The sweep of the auxiliary yarn after withdrawal inevitably clamps it under q and severs it at q'.

Referring now to Fig. 4, the widening 70 pickers 680, 681 may be controlled together, when it is desired to knit a widened gore, by the lift rod 684 having a finger 685 reacting with crank arms 686 on and tending to rock the horizontal element of the usual universal mounting of the widened pickers to throw them downwardly from the position shown in Fig. 15 to the position shown in Fig. 17.

75 In machines of the kind described the length of stitch is controlled by lifting and lowering the column 280, for which the lever 281 reacts on a lug on the column 280 as determined by cams on the drum 120, but when it is desired to knit split tubular fabric it is not desirable to move the drum 120 through 80 considerable distances during reciprocal knitting, and it is preferred to control the stitch lengths for the ankle and foot independently. Referring to Figs. 1, 19 and 20, the stitch length lever 281 is forwardly extending at 281^a 85 to provide for bearing screws resting respectively on a disk 83^b attached to the shaft 80 and on a cam 83^d formed on the hub of an independently movable ratchet wheel 83^a having a segment without teeth. The ratchet 90 83^a is free to rotate on the reduced end of the shaft 80, and may be stepped forward by a pawl plate 71 on the end of a pawl lever 72 pivoted at 73 on a bent lever arm 74 wiped by the hub of pawl 82. During the operation of the machine other than for split tubular knitting the pawl 71 reacts ineffectively with the peripheral toothless segment of the ratchet 83^a, Fig. 1. Projecting from the face of ratchet 83^a is a pin 83^c against which a spring detent 83^e on disk 83^b, Fig. 20, is adapted to take to drive the ratchet 83^a with shaft 80 until the pawl plate 71 finds and actuates teeth. There are enough ratchet teeth to move the cams on the hub 83^d 100 through a sufficient arc and during a sufficient time to determine operation of the lever 281 to change the stitch length appropriately during progress of the split tubular knitting. The screw bearing on disc 83^b determines the 105 lower position of lever 281 and the minimum stitch length.

110 The operation of the machine will now be evident. As described above the various agencies of the machine are coordinated by 120 their several connections to the main pattern carried by the shaft 80 and its associated drum 120 to predetermine operation in the order and to the effect above described.

To make the typical product shown in 125 Fig. 23, the needle cylinder and dial being in rotary motion, one of the yarn fingers F' etc. is dropped to operative position, and the cam 382 is entered and then retired to make a starting selvage on a forward motion of drum 120

120; at a succeeding course, the bight-taking and transfer instruments in dial *d* are advanced on a short motion of drum 120 by cams on block *m* to take bights at the places of needles depressed at cam 382; the instruments in the dial retire with their taken bights at the end of a revolution of the needle cylinder; the machine knits plain circular web for the welt *W* for a predetermined number of courses, whereupon chain 88 initiates a forward rack of the shaft 80 and drum 120, during which cams on block *m* are operated to transfer the bights to needles depressed by cam 12 but thereafter entering the main cams to knit. During the transfer operation the advanced needles are effective to prevent any part of the fabric, except the bights of yarn held on the transfer instruments, from accompanying said instruments into the plane of the needles, and also, by standing at either side of the path of an advancing transfer instrument, such advanced needles ensure proper registry of the transfer instrument with the needle which has previously been lowered by the cam 12 and which now rises to enter the withheld bight on the transfer instrument. Thereafter the machine knits as usual the plain fabric leg *L*, desirably having changed yarn after the welt on another short motion of shaft 80 and drum 120. At this yarn change the auxiliary jack cam 368 may be dropped to inoperative position, Fig. 16, by depression of rod 375, Figs. 2 and 19, and the pickers 650 may be lifted by levers 652, 654. When the machine has produced sufficient fabric for the calf of the leg of the stocking, drum 120 is racked forward through several short steps to move lever 281 to shorten the stitches. When the predetermined place for the section *h* at the back of the angle is reached, chain 85 drops pawl 82 into a tooth in rack wheel 81 preceding the teeth 81^a and 81^b, moving shaft 80 and drum 90 sufficiently to shift clutch shifter 92 to change the motion of the machine to reciprocal motion (pinion 35 clutched to shaft 32). The accompanying motion of drum 120 results in changing the yarn at the main cams (thrust bars 460, finger *F*¹ withdrawn, another yarn finger entered); in shifting the latch-ring gap closer; in putting into operative position, in the order named of slide 113^a and deflecting cam *A*; auxiliary cam slide 100 (during passage of needles *n* at end of rotation of cylinder 260); moving slide 131 to enter cam *B*; in dropping auxiliary yarn guide 570 to position to enter yarn on the first reverse stroke before needles *N* pass the auxiliary cams in direction *y*, Fig. 16; moving rod 326 down to release latch 324 and entering web-holder cam 313 at the auxiliary wave in needles *N*.

The machine knits a predetermined number of split tubular reversed courses sutured together at *a*, *b*, until as determined by chain

85, rack wheel 81 is moved forward at the end of stroke of pawl 82 by tooth 81^a to shift to making the heel. This motion does not alter the position of clutch shifter 92, but results in a yarn change at the main feed; in withdrawing slide 100 and the auxiliary cams; in lifting out and latching up the web-holder cam 313, in withdrawing deflector cam *B*, and in moving the gap-closer ring 565 and auxiliary yarn feed guide 570 to the position of Fig. 5, and simultaneously opening clamp *f*⁵ and cutter *f*¹³, if used, and thereafter (after passage by it of the long butts *N*) withdrawing cam *A* and releasing the narrowing pickers 650. The needles *N* are now on an upper path above the main cams, and a narrowed gore for the heel is being knit on a diminishing series of needles *n*.

The chain 85 now initiates a short rack of wheel 81 (pawl 82, tooth 81^b) which results in dropping the widening pickers into action by motion up of arm 685 and rod 684. If the widening pickers accommodate two needle butts at a time, pickers 650 may be left in operation; if the widening pickers take only one needle at a time, the lever 654 may be operated to hold the narrowing pickers out of operation.

When the last needle *n* has been picked down, at the end of the heel *H*, another short rack of wheel 81 restores the devices to the same condition as when beginning the sections *h*, *i*. The formation of sole *s* and foot top *f* now proceeds to line *z*—*z*, Fig. 23, whereupon rack wheel 81 is moved sufficiently to shift the clutch on shaft 32 to cause rotary motion. Concomitantly slide 100 and the auxiliary knitting cams; auxiliary yarn guide 570, web-holder cam 313, deflector cam *A*, the auxiliary yarn clamp and cutter; if used; and deflector cam *B* are moved appropriately to cease function, and cam *C* is entered to depress any needles left too high to knit at the main cams. The main yarn may be exchanged. When the ring of fabric *r*, *r'* has been knit at the main cams by plain circular knitting, rack wheel 81 is moved to shift the clutch to pinion 35. On this motion, cam *A* is entered to switch up the long butts *N*, and then withdrawn. The pickers are operated in the same way as for the heel, and rotary single course knitting at the main cams only is resumed for loopers' rounds; all of the main yarn fingers *F*' to *F*⁵ are thrown out of action to cast off, and at the same time the jack cam 368 is returned to operative position.

During reciprocal knitting from the beginning of the sections *h*, *i*, to the toe, the motion of shaft 80 having at that time turned ratchet 83^a to present teeth to pawl 71, this has moved the cams at 83^a to control the extension 281^a of the stitch-length lever. This has resulted, according to the figure of these cams and the adjustment of the bearing screw

following them, in imposing desirable stitch length adjustment on the fabric above the instep and in the foot, including the heel and toe. The heel and toe may accordingly be 5 knit much slack than the top of the foot and sole.

Since the auxiliary knitting cams 113, 114 are independently mounted, any different relation of tightness of stitch for the sections 10 *h* and *s* to the fabric in leg *L*, at *i* and at *f* may be arranged for by adjustment of their vertical position.

I do not herein claim any invention common to this application and my copending 15 application Serial No. 44,976, filed July 21, 1925, Patent No. 1,783,202.

I claim:

1. In a knitting machine organized for automatic knitting of stockings having in-turned welts, a carrier for bight-taking and transfer implements, implements in said carrier and means for operating them, a needle carrier and needles therein, means reacting between said carriers for driving the said 20 carriers in unison while the said instruments in them are spaced each from the carrier for the other and each other to avoid contact, and main needle cams and a yarn feed guide for the usual knitting purposes; in combination 25 with auxiliary needle cams for forming an auxiliary knitting wave, means for feeding yarn to the auxiliary wave, and means for rendering the auxiliary knitting cams active and inactive in predetermined relation to the 30 operation of said bight-taking and transfer devices, whereby to knit a stocking having split-tubular sections in predetermined relation to a welt having a course of transferred loops.

2. In a knitting machine organized for automatic knitting of stockings having in-turned welts, a carrier for bight-taking and transfer implements, implements in said carrier and means for operating them to take 40 and subsequently transfer bights to knitting needles, a needle carrier and needles therein, means for driving the said carriers in unison while the said implements and the said needles coacting for said operations are in laterally 45 spaced relation to each other and the carriers for each other; and main needle cams and a yarn feed guide for the usual knitting purposes, and for operating needles to receive a transferred loop, in combination with auxiliary needle cams for forming an auxiliary 50 knitting wave, means for feeding yarn to and withdrawing yarn from the auxiliary wave, and means for rendering the auxiliary knitting cams active and inactive in predetermined 55 relation to the operation of said bight-taking and transfer devices, whereby to knit a stocking having split-tubular sections in predetermined relation to a welt having a course of transferred loops.

3. In a knitting machine organized for au-

tomatic knitting of stockings having in-turned 70 welts, a carrier for bight-taking and transfer implements, implements in said carrier and means for operating them, a needle carrier and needles therein, means for driving the said carriers in unison during rotary and reciproca-

tory motion, whereby said implements and the said needles are spaced out of normal contact with each other and the carrier for the other; main needle cams and a main yarn 75 feed guide for the usual knitting purposes, means for knitting heels and toes during reciprocatory motion of said carriers, in combination with auxiliary needle cams for forming an auxiliary knitting wave, means for feeding yarn to the auxiliary wave during reciprocatory motion of said carriers, and means for moving the auxiliary knitting cams to render them active in predetermined relation to the operation of said heel and toe knitting means, and to render them inactive 80 during heel and toe knitting.

4. In a knitting machine organized for automatic knitting of stockings having in-turned 85 welts, a carrier for bight-taking and transfer implements, implements in said carrier and means for operating them, a needle carrier and series of needles therein, means for driving the said carriers in unison, the said implements and the said needles being spaced 90 by said carrier and driving means to avoid contact with each other and the carrier for the other; main needle cams and a yarn feed guide for plain tubular knitting and for coacting with one series of said needles to knit heels and toes, in combination with auxiliary needle cams for forming an auxiliary knitting wave in another series of the 95 needles, means for feeding yarn to the auxiliary wave, and means for rendering the auxiliary knitting cams active and inactive in predetermined relation to the operation of said bight-taking and transfer devices, whereby to 100 knit a stocking having split-tubular sections in predetermined relation to a welt having a course of transferred loops, and means for suppressing activity of said auxiliary devices 105 during heel and toe knitting.

5. A knitting machine for use in making 115 stockings having in succession an inturned integral welt and a section comprising reverse partial courses of interlocked stitches, said machine having therein a needle carrier and series of needles therein, a cam carrier 120 and main stitch cams adapted for rotary knitting on all of said needles and reciprocatory knitting on one series of said needles, yarn guide means for feeding yarn to needles actuated by said stitch cams, and means 125 causing at times relative rotary and at times relative reciprocatory motions between said needles and said cams for heel and toe knitting, in combination with devices for receiving, detaining and transferring bights for a 130

welt, a depressing cam adapted to coact with needles of each series to position them to permit bights to be taken and transferred, an advancing cam for delimiting the taking and transfer of bights to a single course, and means operative at another time in the production of the stocking for deflecting needles of one of said series above the position of said depressing cam during operation on needles of 10 said series to knit.

6. A knitting machine having therein a needle carrier, and series of needles therein, a cam carrier and main stitch cams adapted for rotary knitting on all of said needles and 15 reciprocatory knitting on one series of said needles, yarn guide means for feeding yarn to needles actuated by said stitch cams, and means causing at times relative rotary and at times relative reciprocatory motion between 20 said needles and said cams for stocking knitting, in combination with means acting automatically to initiate and end knitting at an auxiliary wave of motion for knitting in the other series of said needles during reciprocatory motion including means for feeding 25 yarn to needles so moved, auxiliary knitting cams adapted to be moved into and out of coaction with one series of the needles, the means for initiating and ending knitting by 30 reciprocatory motions with the aid of said auxiliary needle wave operating at times preceding and following reciprocatory knitting on needles of one only of said series to make a heel or toe, and comprising means for deflecting needles of the other series above the 35 main stitch cams acting at the position of rest of the respective leading and following needles of adjacent series during reciprocating knitting.

40 7. A knitting machine having therein a needle carrier, and series of needles therein, a cam carrier and main stitch cams adapted for rotary knitting on all of said needles and reciprocatory knitting on one series of said 45 needles, yarn guide means for feeding yarn to needles actuated by said stitch cams, and means causing at times relative rotary and at times relative reciprocatory motion between 50 said needles and said cams for stocking knitting, in combination with means carrying auxiliary stitch cams movable automatically to form and extinguish an auxiliary wave of motion for knitting in the other series of said needles during reciprocatory motion, means 55 for feeding yarn to and withdrawing yarn from needles so moved, means for deflecting the needles knitting at the auxiliary wave above the main stitch cams automatically movable into and out of contact with said 60 needles knitting at the auxiliary wave, and means for deflecting elevated needles of said series into operative contact with said main knitting cams on the resumption of rotary knitting.

65 8. A knitting machine having therein a

needle carrier, and series of needles differentiated in respect to length of needle butts therein, a cam carrier and main stitch cams adapted for rotary knitting on all of said needles and reciprocatory knitting on one 70 series of said needles, yarn guide means for feeding yarn to needles actuated by said main stitch cams, and means causing at times relative rotary and at times relative reciprocatory motions between said needles and said 75 cams for stocking knitting, in combination with deflecting cams asymmetrically placed in respect to said main cams and means acting automatically to move said deflecting cams into and out of contact with the longer 80 butt needles to switch said needles over the main stitch cams and to return them to operative position during reciprocatory motion, auxiliary knitting cams for moving the longer butt series of needles only, means for 85 feeding yarn to needles so moved, and automatic means for initiating and ending knitting by reciprocatory motions with the aid of said deflecting and auxiliary needle cams operating at times preceding and following 90 reciprocatory knitting on needles of one only of said series to make a heel or toe.

9. In a knitting machine, in combination with a needle carrier and means for knitting a stocking on two series of needles by coaction with each of said series in succession for tubular knitting, and with one of said series only to knit heel and toe pockets by reciprocal motions of said carriers, the combination of auxiliary knitting cams and cam means 95 severally movable and in one position adapted to deflect the series of needles not knitting for heels and toes into operative relation to auxiliary stitch cams during reciprocal motions of the said carrier for split tubular knitting, 100 and to deflect said series of needles to an idle level above and out of contact with the main stitch cam during said heel and toe knitting and split tubular knitting, and means to cause the series of needles for knitting heels and toes to pass the auxiliary cams without deflection from their normal idle level.

10. In a knitting machine, in combination with a needle carrier, main and auxiliary stitch cams and different series of needles occupying opposite segments of the carrier, said machine having means for oscillating the needle carrier for reciprocal knitting through an arc of more than half a revolution, whereby the needles of each segment pass entirely by the stitch cams at which they respectively knit, needle deflecting means for needles of one of said series respectively positioned at the end points of the arcs of oscillation in each direction of needles at the junctures between said series, and means for moving said deflecting means severally into and out of position to coact with one series of said needles.

11. In a knitting machine, in combination with a needle carrier, main and auxiliary

- stitch cams and series having longer and shorter butts, respectively, of needles occupying opposite segments of the carrier, said machine having means for oscillating the needle carrier for reciprocal knitting through an arc of more than half a revolution, whereby the needles of each segment pass entirely by the stitch cams at which they respectively knit, needle deflecting means for needles of one of said series respectively positioned at the end points of the arcs of oscillation in each direction of needles at the junctures between said series, and means for moving said deflecting means severally into and out of position to 500
15 coact with one series of said needles, the said means for moving said deflecting means acting severally at times of passage by them of a series of needles having shorter butts.
12. In a knitting machine for knitting fabrics partly of plain circular and partly of split tubular knitting, the combination with a needle carrier and needles and a cam carrier of means for causing relative movements of rotation and reciprocation between said 200
25 carriers, main and auxiliary stitch cams on the cam carrier, movable deflecting means for causing a series of the needles to pass above the main cams and enter the auxiliary cams repeatedly during split tubular knitting, means for causing said deflecting means to leave said needles in inoperative relation to the main cams during heel and toe knitting on the other series of needles at the main cams, and means for causing the heel and 300
35 toe series of needles to pass the auxiliary cams without deflection from their normal idle level.
13. In a knitting machine, in combination, circular knitting devices including series of needles, means for knitting heel and toe pockets on one of said series of needles and means for knitting split tubular fabric on said series of needles by forming on said series severally reversed part-circular courses 400
45 joined by sutures at lateral selvages comprising devices for holding the heel and toe knitting devices out of operation, and means for forming and feeding an auxiliary knitting wave in a series of needles not operated to knit heels and toes, said respective means co-operating at the same level with needle butts substantially equidistant from the needle hooks.
14. In a knitting machine, in combination, circular knitting and welting devices for making an inturned tubular welt, said devices including needles of a plurality of series of needles, means for knitting heel and toe pockets on one of said series of needles, and means for knitting split tubular fabric on said needles by forming, on said series severally, reversed part-circular courses 500
55 joined by sutures at lateral selvages comprising devices for holding the heel and toe knitting devices out of operation, and means 600
65 for forming and feeding an auxiliary knitting wave in a series of needles not operated to knit heels and toes.
15. In a knitting machine, in combination, circular knitting and welting devices for making an inturned tubular welt, said devices including needles of a plurality of series of needles, means for knitting heel and toe pockets on one of said series of needles, and means for knitting split tubular fabric on said needles by forming, on said series severally, reversed part-circular courses 700
75 joined by sutures at lateral selvages in wales intervening between wales of an adjacent section of fabric knit on another series of needles, comprising devices for holding the heel and toe knitting devices out of operation, and means for forming and feeding an auxiliary knitting wave in a series of needles not operated to knit heels and toes.
16. In a dial knitting machine for split tubular work, in combination with an instrument dial, a needle carrier and main needle cams, movable auxiliary stitch cams and means for establishing and extinguishing a 800
85 knitting wave at said auxiliary cams, a movable yarn feed guide adapted to enter and withdraw yarn at the auxiliary feed by motions of its yarn delivering portion to and from a space outside of the needles and below the dial, and above the dial, respectively; means for moving the auxiliary feed guide independently of motion of the said auxiliary devices to establish a wave, and means acting coordinately with motions of said devices 900
95 for establishing the auxiliary wave to enter said auxiliary yarn to operative position.
17. In a dial knitting machine for split tubular work, in combination with an instrument dial, a needle carrier and main needle cams, auxiliary needle cams and means for establishing and extinguishing a knitting wave at said auxiliary cams, a movable yarn feed guide adapted to enter and withdraw yarn at the auxiliary feed by motions of its 1000
105 yarn delivery portion to and from a space outside of the needles and below the dial, and above the dial respectively, means for moving the auxiliary feed guide independently of motion of auxiliary devices to establish a 1100
115 wave to a position preparatory to feeding, and means acting coordinately with motions of said devices for establishing the auxiliary wave to enter said auxiliary yarn to operative position on the first reverse stroke of reciprocating knitting.
18. In a dial knitting machine for split tubular work, in combination with an instrument dial, a needle carrier and series of needles respectively having longer and shorter butts, main needle cams, auxiliary stitch cams adapted when operative to act on longer butt needles only, means for establishing and extinguishing a knitting wave at said auxiliary cams by moving the said stitch cams, a mov- 1200
125

- able yarn feed guide adapted to enter and withdraw yarn at the auxiliary feed by motions of its yarn delivery portion to and from a space outside of the needles and below the dial, and above the dial, respectively, means for moving the auxiliary feed guide independently of the motion of the auxiliary stitch cams to establish a wave, and means acting coordinately with motion of said 5 stitch cams for establishing the auxiliary wave to cause said auxiliary yarn guide to move to operative position on the occurrence of a reversed reciprocal motion of the needles.
15. 19. In a dial knitting machine for split tubular work, in combination with an instrument dial, a needle carrier and main needle cams, auxiliary needle cams and means for establishing and extinguishing a knitting 10 wave at said auxiliary cams, a latch guard ring and a gap-closer ring, a movable yarn feed guide adapted to enter and withdraw yarn at the auxiliary feed by motions to and from a space behind said gap-closer outside of 15 the needles and below the dial, and above the dial, respectively, means for moving the auxiliary feed guide, and means acting coordinately with motions of said means for establishing the auxiliary wave to move a gap in 20 said gap-closer ring opposite said space and to enter said auxiliary yarn to operative position.
20. In a split-tubular stocking-knitting machine, a needle carrier and a plurality of 35 series of needles therein differentiated from each other, means including needle pickers cooperating with main stitch cams for knitting heels and toes on needles of one of said series, means for causing relative motion reciprocally between the needle carrier, needle 40 pickers and main stitch cams for this purpose, in combination with means for causing such reciprocal motion for split-tubular knitting for other parts of the stocking, and 45 means for acting on a series of needles not acted upon during heel and toe knitting for knitting a complementary part of a split tube comprising means for restraining the 50 said needle pickers from operation, and auxiliary knitting cams positioned out of contact with needles of the heel and toe series.
21. In a knitting machine organized for 55 automatic knitting of stockings having in-turned welts, a carrier for bight-taking and transfer implements, implements in said carrier and means for operating them, a needle carrier and needles therein, main needle cams and a yarn feed guide for the usual knitting purposes, auxiliary needle cams for forming 60 an auxiliary knitting wave, means for feeding yarn to the auxiliary wave, and means for rendering the auxiliary knitting cams active and inactive in predetermined relation to the operation of said bight-taking and 65 transfer devices, in combination with a series 70 of web-holders, means for entering into and removing from contact with the web-holders an auxiliary web-holder cam for forming a wave of web-holder motion in relation to the auxiliary needle wave, whereby the web-holders devices may cooperate with normally positioned web-holders.
22. In a knitting machine for split foot knitting at main and auxiliary knitting waves in needles, in combination, web-holders 75 adapted to be actuated in relation to said waves, means for causing rotary and reciprocatory motion relatively between the needles and web-holders and actuating cams therefor, a web-holder cam device for actuating the web-holders at the auxiliary wave having freedom of motion to shift the position of its wave relatively to the needles on reciprocatory motion, and adjusting means 80 for said cam device adapted to form or extinguish the web-holder wave by motion into and out of contact with the web-holders having a connection to pattern devices operative in any position of the web-holder cam device.
23. In a dial knitting machine for split 85 tubular work, in combination with an instrument dial and dial caps therefor, a needle carrier and main needle cams, main yarn feed guides, auxiliary needle cams and means for establishing and extinguishing a knitting 90 wave at said auxiliary cams, a movable yarn feed guide adapted to enter and withdraw yarn at the auxiliary feed by motions of its 95 yarn delivery end to and from a space outside of the needles and below the dial, and above the dial cap, respectively, means for moving said feed guide from idle to an intermediate position, means coordinated with the establishment of the auxiliary knitting wave 100 for completing the movement of the feed 105 guide to its operative position, means above the dial cap to receive, sever and hold withdrawn main yarns, means for actuating said severing devices, and means operative upon entry into it of a withdrawn yarn for receiving, severing and holding a withdrawn yarn 110 from said auxiliary yarn feed.
24. In a dial knitting machine for split 115 tubular work, in combination with an instrument dial and dial cap therefor, a needle carrier and main needle cams, main yarn feed guides, auxiliary needle cams and means for establishing and extinguishing a knitting 120 wave at said auxiliary cams, a movable yarn feed guide adapted to enter and withdraw 125 yarn at the auxiliary feed by motions to and from a space outside of the needles and below the dial, and above the dial cap, respectively, means for moving said feed guide from idle to an intermediate position, means coordinated with the establishment of the auxiliary knitting wave for completing the movement of the feed guide to its operative position, means above the dial cap to receive, sever and hold withdrawn main yarns, means 130

for actuating the severing devices, and means for receiving, severing, and holding a withdrawn yarn from said auxiliary yarn feed, comprising a clamp operative on entry of the 5 yarn and a fixed cutter swept by the withdrawn yarn.

Signed by me at Philadelphia, Pennsylvania, this twenty-fourth day of May, 1928.

JOHN L. SUTPHEN.
